UNITED STATES PATENT OFFICE.

FRANK W. PRATT, OF AMBRIDGE, AND BRUCE JOHN DICKINSON, OF FAIR OAKS,
PENNSYLVANIA.

TOY CATAPULT.

1,072,988.

Specification of Letters Patent.

Patented Sept. 9, 1913.

Application filed October 30, 1912. Serial No. 728,751.

To all whom it may concern:

Be it known that we, FRANK W. PRATT and BRUCE JOHN DICKINSON, citizens of the United States, and residents, respectively, 5 of Ambridge, in the county of Beaver and State of Pennsylvania, and of Fair Oaks, in the county of Allegheny and State of Pennsylvania, have invented a new and useful Toy Catapult, of which the following is a 10 specification.

The invention relates to improvements in spring catapults.

The object of the present invention is to improve the construction of catapults for 15 throwing shot, stone, or other missiles with force and accuracy without the use of elastic or rubber.

A further object of the invention is strength and durability, not liable to injury by ordinary usage and highly efficient 20 for the purpose intended, a simple inexpensive catapult.

With these and other objects in view, the invention consists in the novel construction, 25 combination and arrangement of parts hereinafter fully described, illustrated in the accompanying drawing, and pointed out in claims hereto appended.

Reference will now be had to drawing 30 wherein—

Figure 1 is top view of Fig. 2. Fig. 2 is front view of the catapult. Fig. 3 is view of side of Fig. 2. Fig. 4 is view of the catapult with horizontal arms of vertical coiled 35 springs brought to a central position and retained in that position by having a pin or bar passing through loop on each end of arms. This arrangement enables the catapult to be carried in a flat position. Fig. 40 5 view showing how the catapult is manipulated.

A catapult in accordance with the invention comprises members, 1 oblong loop in metal forming handle, 2 metal twisted 45 together, 3 and 4 bottom horizontal bars, 5 and 6 vertical side posts connected to bottom horizontal bars, 7 top horizontal cross bar connected to vertical side posts 5 and 6, 8 loop used as sight and connected to top 50 horizontal cross bar 7, 9 and 10 coiled springs with horizontal arms, springs 9 and 10 mounted on vertical posts 5 and 6 and working in opposite directions as shown in Fig. 1, 11 and 12 horizontal arms of springs 9 55 and 10, 13 webbing or other pliable mate-

rial and connected to arms 11 and 12, 14 and 15 dotted lines show arms 11 and 12 drawn back in position for throwing shot or missile, 16 and 17 dotted lines show arms 11 and 12 after being released and springing 60 beyond the natural position of arms. This movement of the arms is very necessary as it brings the webbing 13 taut with a snap which causes the shot or missile to leave the webbing with great rapidity. 65

This catapult can be made of various sizes.

We claim,

1. A toy catapult comprising a frame provided at one side with a handle and at its 70 opposite side with a sight, a pair of spring controlled arms carried by the ends of said frame and adapted to be pulled rearwardly through the frame prior to the projecting of the missile, a flexible actuating band for the 75 missile having its ends connected to the free ends of said arms, and each of said arms having its end provided with a loop for the reception of a bar to maintain said arms parallel with the sides of said frame. 80

2. A toy catapult comprising a rectangular frame having one side thereof provided with a handle, a coiled spring mounted upon each end of said frame, and extended intermediate its ends of and providing an arm 85 normally projecting at right angles with respect to said end, the said springs working in opposite directions with respect to each other and said arms capable of being pulled rearwardly through the frame prior to the 90 projecting of a missile, and a flexible missile projecting strip connecting said arms together. 95

3. A toy catapult comprising a rectangular frame having one side thereof provided with a handle, a coiled spring mounted upon each end of said frame and extended intermediate its ends of and providing an arm normally projecting at right angles with respect to said end, the said springs working 100 in opposite directions with respect to each other and said arms capable of being pulled rearwardly through the frame prior to the projecting of a missile, and a flexible missile projecting strip connecting said arms together, said frame having the other side thereof provided centrally with a sight. 105

4. In a toy catapult comprising a rectangular frame having one side thereof provided with a handle, a coiled spring mounted 110

- upon each end of said frame and extended intermediate its ends of and providing an arm pivotally projecting at right angles with respect to said end, the said springs 5 working in opposite directions with respect to each other and said arms capable of being pulled rearwardly through the frame prior to the projecting of a missile, a flexible missile projecting strip connecting said arms together, 10 and each of said arms having its free end provided with a loop, said loops adapted to receive a bar for maintaining the arms parallel with the sides of the frame.
5. A toy catapult comprising a rectangular frame having one side thereof provided with a handle, a coiled spring mounted upon each end of said frame and extended intermediate its ends of and providing an arm 15

normally projecting at right angles with respect to said end, the said springs working 20 in opposite directions with respect to each other and said arms capable of being pulled rearwardly through the frame prior to the projecting of a missile, a flexible missile projecting strip connecting said arms together, 25 said frame having the other side thereof provided centrally with a sight, and each of said arms having its free end provided with a loop, said loops adapted to receive a bar for maintaining the arms parallel with the sides of the frame.

FRANK W. PRATT.

BRUCE JOHN DICKINSON.
